AMPLIFIER WITH RISING FREQUENCY
RESPONSE

Robert C. Moore, Philadelphia, Pa., assignor to
Phileo Corporation, Philadelphia, Pa., a corporation of Pennsylvania

Application June 20, 1946, Serial No. 678,014

4 Claims. (Cl. 179—171)

1

This invention relates to vacuum tube amplifiers and particularly to a novel and improved amplifier having a signal transfer characteristic which rises with frequency throughout the higher frequency portion of its range. Such a device has particular application in the so-called head amplifier in a television camera system, where it serves to compensate the input impedance characteristic of the head amplifier fed by the usual camera tube. It is, of course, suited to any application where a response, substantially uniform for lower frequency components but peaked for higher frequency components, is desired.

Accordingly, a principal object of the invention is to provide an amplifier having substantial gain for lower signal frequency components and having a rising response for signal frequency components in the higher frequency portion of its range.

Another object is to provide an amplifier in which these characteristics are achieved by the use of separate signal paths; one path contributing to the output of the amplifier principally in one range of the frequency band, and the other contributing appreciably only throughout the remainder of the band.

Still another object is to provide an amplifier of this sort in which one of the paths includes a coupling between the plate of a first amplifier tube and the grid of a second; while the other path includes an impedance common to the cathode circuits of both tubes.

A further object of the invention is to provide a two-path amplifier having the desired signal transfer characteristic, while avoiding regeneration at certain frequencies and oscillation which may result therefrom.

Another object of the invention is to provide a two-path amplifier in which use is made, in one of the paths, of a load inductor having fortuitous resistance, and in which means are provided for compensating the effect of said resistance so that said path will provide a substantially uniformly rising signal transfer characteristic.

Other objects and advantages of the invention will become apparent from a consideration of the following specification together with the drawings in which:

Figure 1 is a schematic diagram of a two-stage vacuum tube amplifier in accordance with the invention, and

Figure 2 is a graphic representation of the signal transfer characteristic of the amplifier as a whole, showing also the contributions of the separate paths.

2

Referring to Figure 1, input signal to the amplifier may be supplied through coupling condenser C_1 to the grid of pentode vacuum tube T_1 . In the plate circuit of tube T_1 is connected a load inductor L_1 , including its inherent fortuitous resistance represented by resistor R_2 . Signal developed across this load impedance is supplied through coupling condenser C_2 and across grid leak resistor R_3 to the control grid of a subsequent pentode T_2 . In addition to the signal transfer path between tubes T_1 and T_2 as just described, an additional path is provided comprising resistor R_5 , shunted by condenser C_3 and common to the cathode circuits of both tubes T_1 and T_2 .

Assuming the plate load impedance of tube T_1 to be purely inductive, the transfer of signal from tube T_1 to tube T_2 by a coupling condenser C_2 and grid leak resistor R_3 would be substantially as represented by the sloping broken line a of Figure 2. This provides the desired rising signal transfer characteristic for higher signal frequency components. The resistor R_5 in the cathode circuits of tubes T_1 and T_2 , on the other hand, provides a signal transfer characteristic as represented by the broken line b in Figure 2. These two responses will be 90 degrees out of phase and one will therefore complement the other to yield an over-all characteristic as represented at c in Figure 2, having the desired rising response for the higher frequency components, while at the same time providing for a reasonable degree of amplification of the components in the lower frequency range. The condenser C_3 in shunt with resistor R_5 is provided to reduce the gain through the cathode path at the higher frequencies so as to prevent undesired regeneration at these frequencies which might tend to cause the amplifier to become oscillatory.

Furthermore, it is to be noted that if the plate load inductor L_1 possesses any appreciable amount of fortuitous resistance, this will tend to increase the gain for lower frequencies through the path from the plate of tube T_1 to the grid of tube T_2 . To avoid this, it is therefore desirable, in certain applications of the circuit (e. g. in a television head amplifier), either to minimize the fortuitous resistance R_2 or to compensate for it, as may be done by proper adjustment of the coupling network C_2 , R_3 . To eliminate completely the effect of R_2 and to obtain results equivalent to those which would be obtained with a purely inductive load, the values of C_2 and R_3 should be such as to satisfy the relationship

$$C_2 R_3 \approx \frac{L_1}{R_2}$$

In other applications the value of R_2 may be used to control the shape of the low frequency response characteristic.

Thus, it is apparent that the resistor R_5 is effective, primarily at lower frequencies, and the inductor L_1 is effective, primarily at higher frequencies, to produce the composite curve C, with its flat contour at lower frequencies, moving into steadily rising values at higher frequencies.

In a typical circuit according to Figure 1 for use in a television system between the camera tube and the head amplifier, where the input to the head amplifier was equivalent to a parallel RC circuit having a resistance of 220,000 ohms and a capacitance of $15 \mu\mu$ farads, and using two type 6AC7 tubes for T_1 and T_2 , the values of the critical circuit elements were chosen as follows:

L_1	μ henries	18
R_2	ohms	0.5
C_2	μ farad	0.007
R_3	ohms	4,700
C_3	μ farad	0.1
R_5	ohms	5.5

It will be understood, of course, that the foregoing values apply only to one particular case and that the values of the circuit parameters and the types of tubes used may be varied considerably depending on circumstances, without departing from the scope of the invention as defined by the appended claims.

I claim:

1. In an electrical signal amplifier, first and second amplifier stages, each comprising a vacuum tube having at least triode elements, an essentially inductive load in the plate circuit of said first tube and coupling from the plate of said first tube to the grid of said second tube to provide a rising signal transfer characteristic between said stages with increasing frequencies, and an impedance common to the cathode circuits of both of said tubes and adapted to provide relatively high signal transfer between said stages only for relatively low signal frequency components, said impedance comprising a parallel-connected resistor and condenser.

2. In an electrical signal amplifier, first and second amplifier stages, each comprising a vacuum tube having at least triode elements, a load impedance in the plate circuit of said first tube, said load impedance comprising an inductance L_1 , and an inherent resistance R_2 , a condenser of capacitance C_2 connecting the plate of said first tube to the grid of said second tube and a grid-leak resistor of resistance R_3 connecting said grid to a point of predetermined potential, the values of C_2 and R_3 being such that C_2R_3 is approximately equal to L_1/R_2 , whereby said condenser and said grid-leak resistor cooperate with said load inductor to compensate the effect of said inherent resistance and to provide an essentially

uniformly rising signal transfer characteristic between said stages with increasing frequencies, and an impedance common to the cathode circuits of both of said tubes and adapted to provide relatively high signal transfer between said stages only for relatively low signal frequency components, said impedance comprising a parallel-connected resistor and condenser.

3. In an electrical signal amplifier, first and second amplifier stages, each comprising a vacuum tube having at least triode elements, an essentially inductive load in the plate circuit of said first tube, a coupling from the plate of said first tube to the grid of said second tube to provide a rising signal transfer characteristic between said stages with increasing frequencies, and an impedance including a resistor and capacitor common to the cathode circuits of both of said tubes and adapted to provide relatively high signal transfer with a declining signal transfer characteristic between said stages only for relatively low signal frequency components, whereby a composite signal characteristic is secured with approximately uniform values for lower signal frequencies and with increasing values for higher frequencies.

4. A vacuum tube amplifier for use in the head amplifier of a television camera system to provide a frequency response characteristic comprising substantially uniform response throughout a relatively low frequency range and a response rising substantially uniformly with frequency for frequencies above said range, for compensating the input impedance characteristic presented by said amplifier to the television camera tube, said amplifier comprising first and second amplifier stages each including a vacuum tube having at least triode elements, a load impedance in the plate circuit of said first tube comprising an inductance having negligible inherent resistance, a condenser coupling the plate of said first tube to the grid of said second tube, a grid-leak resistor connecting the grid of said second tube to a point of predetermined potential, and an impedance common to the cathode circuits of both of said tubes, said last-named impedance including a resistor and a condenser connected in parallel, said plate and cathode load impedances cooperating to provide said frequency response characteristic.
